UNITED STATES PATENT OFFICE.

WILLIAM J. GAGNON, OF BRIDGEPORT, CONNECTICUT, ASSIGNOR TO THE BRYANT ELECTRIC COMPANY, OF BRIDGEPORT, CONNECTICUT, A CORPORATION OF CONNECTICUT.

BEAD CHAIN.

1,117,829.

Specification of Letters Patent.

Patented Nov. 17, 1914.

Application filed July 9, 1913. Serial No. 778,102.

To all whom it may concern:

Be it known that I, WILLIAM J. GAGNON, a citizen of the United States of America, residing in the city of Bridgeport, in the

5 county of Fairfield and State of Connecticut, have invented certain new and useful Improvements in Bead Chains, of which the following is a specification.

The object of my invention is to provide 10 a simplified form of bead chain, consisting of a series of flexibly connected beads, each bead carrying its own means of connection with the next.

The construction will be understood from 15 the following description:—

In the accompanying drawing, Figure 1 is a view, mainly in longitudinal section, showing, on an enlarged scale, a piece of bead chain constructed in accordance with 20 my invention; Fig. 2 is a corresponding side view; Fig. 3 is an end view of one of the beads.

Each bead of my improved chain is formed 25 out of tubular material, of approximately the diameter of the largest part of the bead. This large part of the bead is a hollow ball A, preferably almost spherical but with a tubular neck a and a head b on the outer end of the neck. In the course of manu- 30 facture, the head of the neck of each bead is to be inclosed within the hollow ball of the

next bead, the neck having the requisite freedom of movement within the opening c of such hollow bead, as will be readily understood.

35

I claim as my invention:—

1. A bead chain, consisting of a series of flexibly connected beads, each a hollow ball with a substantially closed tubular neck and a closed head thereon to be contained within 40 the ball of an adjacent bead, substantially as described.

2. A bead chain, consisting of a series of flexibly connected beads, each a hollow ball with a substantially tubular neck and a circular closed head thereon to be contained within the ball of an adjacent bead, substantially as described.

45 3. A bead chain consisting of a series of flexibly connected beads, each bead comprising a substantially spherical ball having thereon a neck of relatively small diameter and a flattened spherical head on said neck contained within the ball of the adjacent bead, substantially as described.

50 55 In testimony whereof I have signed my name to this specification, in the presence of two subscribing witnesses.

WILLIAM J. GAGNON.
